US00D736724S

(12) **United States Design Patent**
Shum et al.

(10) **Patent No.:** US D736,724 S
(45) **Date of Patent:** ** Aug. 18, 2015

(54) **LED LAMP WITH ACCESSORY**

(71) Applicant: **SORAA, INC.**, Fremont, CA (US)

(72) Inventors: **Frank Shum**, Fremont, CA (US);
Clifford Jue, Fremont, CA (US); **Artem Mishin**, Fremont, CA (US); **Zinovy Dolgonosov**, Fremont, CA (US); **George Xie**, Fremont, CA (US); **Michael Ragan Krames**, Fremont, CA (US); **Jinhui Zhai**, Fremont, CA (US)

(73) Assignee: **Soraa, Inc.**, Fremont, CA (US)

(**) Term: **14 Years**

(21) Appl. No.: **29/458,298**

(22) Filed: **Jun. 18, 2013**

Related U.S. Application Data

(63) Continuation-in-part of application No. 29/441,108, filed on Dec. 31, 2012, and a continuation-in-part of application No. 29/458,826, filed on May 14, 2013, which is a continuation-in-part of application No.

(57) **CLAIM**

The ornamental design for LED lamp with accessory, as shown and described.

DESCRIPTION

FIG. 1 is a perspective view of an LED lamp with accessory showing our new design;

FIG. 2 is another perspective view thereof;

FIG. 3 is a side elevational view from a front side thereof;

FIG. 4 is a side elevational view from a rear side thereof;

FIG. 5 is a side elevational view from a left side thereof;

FIG. 6 is a side elevational view from a right side thereof;

FIG. 7 is a top plan view thereof; and,

FIG. 8 is a bottom plan view thereof.

The broken lines in the figures represent unclaimed subject matter and form no part of the claimed design.

1 Claim, 8 Drawing Sheets
